UNITED STATES PATENT OFFICE.

ELLSWORTH E. FLORA, OF CHICAGO, ILLINOIS, ASSIGNOR OF ONE-HALF TO W. E. ROTHERMEL,
OF CHICAGO, ILLINOIS.

CRATE.

No. 893,576.

Specification of Letters Patent.

Patented July 14, 1908.

Application filed December 18, 1907. Serial No. 407,009.

To all whom it may concern:

Be it known that I, ELLSWORTH E. FLORA, a citizen of the United States, residing at Chicago, in the county of Cook and State of Illinois, have invented a new and useful Improvement in Crates, of which the following is a specification.

The object of my invention is to provide a novel construction of wire-bound crate (including the articles known as a ventilated box and ventilated barrel) which shall render it strong and cheap to manufacture and adapt it to be furnished to the user in knock-down condition to be readily reduced therefrom into crate-form without the exercise of skill or the use of machinery or tools in performing the work.

In the accompanying drawings, Figure 1 is a plan view of a section or length of the wire-jointed slat-material used for the body of my improved crate; Fig. 2, a view in the nature of a diagram illustrating the manner of starting the assembling of the parts to produce the crate; Fig. 3, a similar view, showing the assembling work in a more advanced condition; Fig. 4, a longitudinal vertical section of the crate; Fig. 5, a section on line 5 of Fig. 4, viewed in the direction of the arrow; Fig. 6, a section on line 6 of Fig. 4, viewed in the direction of the arrow, and Fig. 7, a perspective view of one of the heads, or of a similarly formed partition, showing its preferred construction.

For the body-portion of my improved crate, I use a suitable length of slat-fabric 8 (Figs. 1, 2, 3) consisting of slats 9 formed preferably of strips of thin wood or veneer, of fiber-board, or metal, or even of any suitable refuse-material, since it is not essential that the strips shall be of uniform dimensions, except in the matters of length and width, and wires 10 connecting the strips, at suitable intervals along their lengths, in spaced relation, each binding 10 shown being double to embrace the strips, between which it is twisted as represented at 11. A known variety of fencing is manufactured involving the same construction as the material 8, and machinery is employed for forming or "weaving" it in very long lengths to be furnished to the trade rolled into bundles. The material 10 for my crate may be manufactured by the same machinery and similarly furnished, with the end-

heads 12, and intermediate head or partition 13, to the user to enable him to divide the material into suitable lengths and assemble them and the heads into crates 14.

Each end-head and partition (if the latter be used, though no internal head is required in a short crate) conforms in shape to the contour of the crate and may therefore be provided in any shape for the latter. As shown, it is of general rectangular shape with beveled corners, and involves, as its essential construction, a body-portion having tongues 15 extending from its edges, some from the inner and some from the outer parts of the edges. It is preferred to so arrange the tongues that those on two opposite edges shall project from the outer portions thereof and those on the other two opposite edges shall project from their inner portions, as most clearly shown in Fig. 7. Moreover, while the head may be formed of one piece of any suitable material, it is preferred to form it of two similar sections of suitable wood, each having tongues 15 projecting from its opposite edges and extending in the direction of the grain of the wood for the sake of strength to the tongues; and the two pieces or sections are fastened flatwise together, as by gluing or nailing, being relatively so placed as to cause the grain of one piece to cross that of the other at right-angles. Thus the tongues are caused to alternate on the inner and outer edge-portions, from one edge to the other, as described, and for the purpose hereinafter explained.

To assemble the parts to form a crate, the heads therefor are placed and suitably supported at the required distances apart upon a proper length of the material 8 for a crate-body, as indicated in Fig. 2, when the material is wrapped about them in the manner indicated in Fig. 3. Owing to the relative positions of the tongues, which are so spaced as to cause them to enter between slats of the material 8 in applying the latter, those on the inner edges of the end-heads and corresponding edges of the partition will extend at one side of the wires at 11 while those on the opposite edges will there extend at the opposite sides of the wires, thus causing the tongues to brace the wires in opposite directions with the result of securely holding the end-heads against displacement from inward or outward pressure against them and the

partition against displacement from pressure against either of its sides, and with the further result of affording a very strong structure due to the bracing referred to and the intermeshing of the slats and tongues.

The free ends of the wires 10 are left sufficiently long to adapt them to be twisted together, as shown at 16 (Fig. 5), for fastening in their assembled condition the parts of the 10 crate to close it after it is filled. A side of the body-portion from which a wire-end 16 extends may form the cover or lid of the crate to be opened and closed in using the latter, the other sides meantime remaining 15 in place by the intermeshing engagement of the tongues and slats, and the frictional contact between the tongues and wires.

As will be understood, other binding means besides the particular wire-form 20 thereof herein shown and described, may be used without departure from my invention.

What I claim as new and desire to secure by Letters Patent is—

1. A crate comprising a body-portion 25 formed of wire-connected spaced slats, and heads having tongues projecting from them to enter the spaces between slats and said tongues being disposed on each head to extend on opposite sides of a wire connecting 30 the slats, for the purpose set forth.

2. A crate comprising a body-portion formed of wire-connected spaced slats and end-heads and an inner head between the 25 end-heads having tongues projecting from them to enter the spaces between slats and said tongues being disposed on each head to

extend on opposite sides of a wire connecting the slats, for the purpose set forth.

3. A crate comprising a body-portion formed of wire-connected spaced slats, and 40 heads each formed of two sections secured flatwise together and having tongues projecting from them to enter the spaces between slats and said tongues being disposed on each head to extend on opposite sides of a wire connecting the slats, for the purpose set forth.

4. A crate comprising a body-portion formed of wire-connected spaced slats, and 45 heads each formed of two sections secured flatwise together and having tongues projecting from opposite edges of one section and from opposite edges of the other section, but at right-angles to those in the first-named section, said tongues on each head 50 entering the spaces between slats and extending on opposite sides of a wire, for the purpose set forth.

5. A crate comprising a body-portion formed of wire-connected spaced slats, and 55 heads each formed of two wooden sections secured flatwise together with their grains crossing and each having tongues projecting in the direction of the wood from opposite edges to enter the spaces between slats and 60 extend on opposite sides of a wire, for the purpose set forth.

ELLSWORTH E. FLORA.
